US00D845796S

(12) **United States Design Patent** (10) Patent No.: **US D845,796 S**
(45) Date of Patent: **** Apr. 16, 2019**

(54) **RULER**

(71) Applicant: **Tomoki Yamashita**, Higashiosaka (JP)

(72) Inventor: **Tomoki Yamashita**, Higashiosaka (JP)

(**) Term: **15 Years**

(21) Appl. No.: **35/504,717**

(22) Filed: **Oct. 5, 2017**

(80) **Hague Agreement Data**

Int. Filing Date: **Oct. 5, 2017**

Int. Reg. No.: **DM/099854**

Int. Reg. Date: **Oct. 5, 2017**

Int. Reg. Pub. Date: **Apr. 6, 2018**

(30) **Foreign Application Priority Data**

Apr. 5, 2017 (JP) 2017-7271

(51) **LOC (11) Cl.** **10-04**

(52) **U.S. Cl.**

USPC **D10/71**

(58) **Field of Classification Search**

USPC D10/71; D9/434

See application file for complete search history.

(57) **CLAIM**

The ornamental design for a ruler, as shown and described.

DESCRIPTION

1. Ruler

1.1 : Front

1.2 : Back

1.3 : Top, the bottom being a mirror image thereof

1.4 : Right, the left side being a mirror image thereof

1.5 : Partial enlarged reference view

1.6 : Perspective view in state of use

The evenly spaced broken lines depict unclaimed environmental subject matter. The dash-dot-dash lines represent the boundary of the claim.
